UNITED STATES PATENT OFFICE.

AMBROSE MONELL, OF HOMESTEAD, PENNSYLVANIA.

MAGNETIC LIFTING DEVICE.

SPECIFICATION forming part of Letters Patent No. 621,267, dated March 14, 1899.

Application filed May 12, 1898. Serial No. 680,505. (No model.)

To all whom it may concern:

Be it known that I, AMBROSE MONELL, of Homestead, in the county of Allegheny and State of Pennsylvania, have invented a new and useful Improvement in Magnetic Lifting Devices, of which the following is a full, clear, and exact description, reference being had to the accompanying drawings, forming part of this specification, in which—

10 Figure 1 is a side elevation, partly in section, showing one form of my improved apparatus adapted for picking up sheets or plates of relatively thin cross-section. Fig. 2 is a top plan view of the same, and Fig. 3 is an end elevation thereof.

15 My invention relates to the picking up and holding of pieces of metal of any shape by means of electromagnets. It is primarily designed for picking up and carrying about these pieces to any desired point. It enables me to pick up from a pile of iron or steel articles any one of these articles without exerting sufficient attraction upon another or others of the articles to cause them to be picked up with the one article desired to be lifted, while at the same time the magnets are sufficiently strong to lift a number of the articles, or even the whole pile, provided they are mechanically tied to the article lifted.

20 My improved device enables me to pick up articles having considerable range as to weight and thickness or size, while at the same time the above-named functions are carried out.

To that end my invention consists in a series of magnets the lifting power of which is proportioned to lift the heaviest weight desired and each magnet being proportioned so that the magnetic lines between its poles will be practically completed through the smallest thickness of article to which it is applied, these magnets being carried on an equalizing-support which distributes the lifting strain equally among them. By using the series of magnets proportioned and supported in this manner I am enabled to lift from a pile of iron or steel articles any one of these articles without moving the others in proximity thereto and at the same time to exert any required amount of lifting force on the individual article and to afford a large factor of safety. Heretofore in magnetic lifting devices of this character the difficulty has always occurred

that when a magnet was so proportioned as to retain a reasonable factor of safety in picking up certain articles it was not adjusted so as to do only the work required and no more. With these former devices, therefore, it was found almost impossible to pick up one article from a pile, especially if these articles were of different weights, without lifting one or more others from the pile.

In applying my invention to the picking up of broad flat pieces of material—such as slabs, plates, sheets, &c.—I employ a series of electromagnets, these being sufficient in number to give the desired lifting force for the heaviest weight to be lifted with a large factor of safety, while the size of each individual magnet is so proportioned that its magnetic lines of force will be substantially completed through the thinnest plate, slab, or sheet to be lifted—that is, the heaviest weight to be lifted governs the number of the electromagnets, while the smallest cross-section or thickness to which the magnet is applied—that is, between the poles of the magnet—governs the size and design of the individual magnets. These magnets are mounted on an equalizing-support which distributes the lifting strain equally among them.

80 The instructions just given will make it clear to the practical electrician just how the magnets should be constructed within the principles of my invention, for the direction of the lines of force in any given magnet is easily determinable and the poles should be so related, as above stated, that substantially all the lines of force shall pass through the body to be lifted.

85 In the drawings, in which I show my apparatus as particularly designed for picking up plates, 2 is a lifting-bar centrally and pivotally supported from a chain 3, depending from a trolley or any other desired support, this bar having curved rests 4 at its ends, containing clevises 5, secured by clips 6, within which clevises is secured a cross-bar 7, having swinging bars 8 at its ends. Each bar 8 is provided near its end with curved rests 9 for the curved portions of the cores of ordinary horseshoe-electromagnets 10. Flexible conductors 11 are provided to lead the current to the various magnets, and suitable switches may be provided to energize and deenergize the magnets,

as required. Each of these magnets is so proportioned and designed that when energized the lines of force between its poles will be practically completed through the smallest cross-section of the plate or article to be picked up, while a sufficient number of these magnets is provided to give lifting power enough to raise the heaviest article to be picked up with a large factor of safety.

In operation, the magnets being dropped upon the plate or article (which is within the limits for which the device is designed) and energized, the lines of force of each magnet will be practically completed through this single article, so that there will be no danger of lifting other adjacent articles with the one desired to be lifted. The system of equalizer-bars enables the magnets to adjust themselves to the position in which the article is lying, as well as its shape, so the plates lying at an angle, as well as curved plates, may be picked up and transferred to the desired point. The bars are also arranged so that the lift of the device will be substantially evenly distributed among the magnets. The magnets are of course deenergized to drop the plate at the desired point.

If it is desired to lift more than one plate, clamps or yokes may be employed to fasten the plates temporarily together, and the series of plates will then be lifted if their combined weights are within the limiting weight for which the magnets are proportioned.

In constructing the device, to give a specific example, if it is desired to lift single plates varying in thickness from one-half an inch to two inches and to lift a weight varying from five hundred to seven thousand pounds, each individual magnet will be proportioned so that the lines of force between its poles will all be substantially completed through the half-inch plate, while a sufficient number of magnets will be provided to lift seven thousand pounds with a large factor of safety. Hence it will be seen that in any single plate varying from one-half inch to two inches in thickness and in weight from five hundred to seven thousand pounds the lines of force will be substantially completed through this article and it will be lifted singly from a pile of articles.

The advantages of my invention result from the fact that with a single lifting device a sin-

gle article may be lifted from a pile without danger of lifting any of the adjacent articles, and this article may vary widely between the determined limits for which the apparatus is designed both in cross-section and in weight. The equalizing-bars enable the magnets to adjust themselves to the plate, whether curved or lying at an angle, and the whole system is simple and easily constructed.

Variations may be made in the form of the magnets, as well as in their arrangement and means for support, without departing from my invention, since I consider myself the first to arrange magnets for this purpose according to the principle above stated on an equalizing-support.

I claim—

1. In a magnetic carrying device, a series of electromagnets, the lifting power of the series being proportioned to lift the heaviest weight desired, and each individual magnet being proportioned so that the magnetic lines between its poles will be practically completed through the smallest thickness of article to which it is applied, means for energizing and deenergizing said magnets; and an equalizing-support for the magnets arranged to distribute the lifting strain equally among them substantially as described.

2. In a magnetic carrying device, a pivotal support having pivotal equalizer-bars, and electromagnets carried upon said equalizer-bars, the bars being arranged so that the lifting power will be substantially evenly distributed over the surface among the magnets; substantially as described.

3. In a magnetic carrying device, a pivotal support carrying swinging equalizer-bars and magnets carried upon the equalizer-bars, each magnet being so proportioned that the magnetic lines between its poles will be substantially completed through the smallest thickness of metal to which it is applied, the lifting power of the series of magnets being proportioned to lift the greatest weight desired; substantially as described.

In testimony whereof I have hereunto set my hand.

AMBROSE MONELL.
